L. A. BONNER

HYDRAULIC ELEVATOR

Filed July 13, 1926

UNITED STATES PATENT OFFICE.

LEICESTER A. BONNER, OF VANCOUVER, BRITISH COLUMBIA, CANADA.

HYDRAULIC ELEVATOR.

Application filed July 13, 1927. Serial No. 122,222.

My invention relates to improvements in hydraulic elevators which are particularly adapted for elevating the tailings from sumps in mining operations and the like, 5 the objects of the invention being to obtain increased efficiency over hitherto known types, to obviate wear and breakage of parts and to provide automatic adjustment of the contracted vein in the upcast to conform to 10 the different load conditions imposed upon the elevator. A still further object is to provide means whereby water of reservoirs which have become unpalatable from stagnation may be aerated in large volume and 15 at little cost.

The invention consists essentially of an upcast shaft having a bell adapted to project downwards towards the water level of the sump and a jet through which water is 20 projected upwards through the upcast shaft, said jet being surrounded by an outlet orifice through which air is adapted to flow, as will be more fully described in the following specification, in which:—

25 Fig. 1 is a general view part in section of the invention.

Fig. 2 is a sectional view showing the manner in which the elevator functions.

In the drawings like characters of reference indicate corresponding parts in each figure.

The numeral 1 indicates a sump for receiving the gravel or tailings from the sluicing operation and in which the foot of the 35 elevator, generally indicated by the numeral 2, is mounted. The elevator foot comprises a U bend 3 suitably mounted upon a foundation 4 of concrete or wood, according to the permanence or otherwise of the 40 installation. This U bend is formed gradually diminishing in cross section from the power water supply pipe 5 as at 6 to the jet 7 as at 8, so that the water fed through it from the power supply pipe 5 is materially increased in velocity as it is forced through 45 the outer end of the U. The jet 7 is formed in the usual manner with a restricted outlet 9 which serves to further increase the velocity of water as it passes therethrough.

50 Surrounding the jet 7 is an annular chamber 10 having an air inlet connection 11 and an outlet orifice 12, which latter is concentric with the outlet 9 of the jet 7.

The numeral 13 indicates an air pipe having a valve 14 at its upper end to control the inflow of air to the pipe and being con-

nected at its lower or submerged end to the inlet 11 of the chamber 10. Suitably supported axially above the jet 7 is an upcast pipe 15 having a parallel bore and which is fitted at its upper end with a discharge bend 16, while at the lower end of the pipe a bell or flare piece 17 is fitted which is adapted to extend downwards to within a short distance of the normal level 65 of the water and gravel within the sump 1.

Having thus described the several parts of my invention I will now briefly explain its function.

Water is supplied to the pipe 5 from any 70 suitable source and at any desired pressure according to the lift required, and is projected through the outlet 9 of the jet 7, then passing through the overlay of water in the sump 1 and upwards through the upcast 75 pipe 15 and discharge outlet 16. During the starting of the flow of water through the jet the valve 14 is left open to admit a flow of air to be drawn through the pipe 13, and the annular chamber 10 to discharge through 80 the concentric outlet orifice 12 around the jet 7. When the elevator has been started adjustment is effected by closing down the valve 14 to restrict the flow of air through 85 the outlet orifice 12, thus permitting a more intimate contact between the gravel or load and the jet water until the maximum amount of load is raised and carried through the upcast to discharge. The flow of air around 90 the jet 7 at substantially atmospheric pressure serves to prevent the too intimate contact of the water and the load to be lifted with the jet water, thus permitting the jet water to be projected through the upcast pipe 15 and the discharge bend 16 and to 95 carry with it a light load. The force of the jet water passing upwards into the upcast pipe draws with it the water from the sump in a converging column, as is indicated in Figure 2 between the dotted lines A—B or 100 until the upward velocity of the two flows are substantially equalized, subsequently, as the velocity decreases and homogeneity of the two flows develops the combined column increases in diameter to approximately the 105 diameter of the upcast pipe as between the dotted lines B—C. Since this contraction of the upflow is developed by the force of the water projected, it naturally follows that the space defined between the contracted 110 portion of the column and the pipe must be filled by air at atmospheric pressure or less,

therefore by providing the upcast pipe with the bell or flare piece 17 air is permitted to enter the pipe in such volume as to permit the space surrounding the contracted length 5 of the column to be filled with air at substantially atmospheric pressure, so that a balanced condition prevails.

Further very important advantages exist in permitting the inflow of air to form a restricted column as shown between the lines 10 A and C obviating the need for inserting a "choke" fitting for this purpose, such as is commonly installed in elevators of this type. One of these advantages is that the air required to form the contracted length of the upcast must be allowed to enter, and in entering the bell 17 it forms an air cushion surrounding the bell and the pipe which prevents friction or breakage between the solids 15 elevated and the surfaces of the pipe. Since a continuous flow of air passes upwards through the bell it will be readily seen that an equal flow will continue throughout the length of the upcast pipe, this flow continues to act as an annular cushion preventing skin friction between the jet and load water 20 and the side walls of the pipe.

Another advantage lies in the fact that the contracted portion of the column may 25 vary in length or in position within the upcast pipe according to variation of the velocity of the jet water and the load without meeting with any obstruction such as would prevail, were a "choke" fitted.

Should it be desired to use the elevator for aerating water for drinking or any other purpose, air may be forced under any desired pressure through the outlet orifice 12 surrounding the jet, which would produce 30 a complete occlusion of the water raised by the air projected therefrom.

What I claim as my invention is:

1. A hydraulic elevator comprising an upcast pipe having an upper discharge opening and a lower inlet opening adapted to be set above the surface of the matter to be elevated so as to provide for the entrance of air to form a cushion between the inner surface of the pipe and the matter being elevated therein, and means adapted to induce an upward current in the upcast pipe, said upcast pipe having parallel sides for an appreciable distance above the inlet opening.

2. A hydraulic elevator for load water and its solids comprising an upcast pipe having an unrestricted bore, a discharge outlet and a load receiving bell adapted to be set slightly above the load water level so as to permit atmospheric air to flow into said bell to form a cushion between the inner

surface of the pipe and the column of water passing upwardly therethrough, a water jet below the water level and aligned axially with the upcast pipe through which power 65 water is adapted to be projected upwards into the pipe to raise the load water and its solids for discharge through the discharge outlet.

3. A hydraulic elevator for load water 70 and its solids comprising an upcast pipe having a discharge outlet and a load receiving bell spaced above the surface of the load water to permit atmospheric air to freely enter the lower end of the bell to 75 form a film or cushion between the inner surface of the pipe and the load water passing upwardly therethrough, a water jet axially aligned with the upcast pipe through which power water is adapted to be projected upwards into the pipe to raise the load 80 water and its solids through the discharge outlet, and means for introducing an annular upflow of air between the power water jet and the load water when entering the upcast pipe, said up flow being at atmospheric 85 pressure or less.

4. A hydraulic elevator for load water and its solids comprising an upcast pipe having a discharge outlet and a load receiving 90 opening spaced above the surface of the load water to permit atmospheric air to enter between the load water and the inner surface of the pipe, a submerged water jet 95 axially aligned with the upcast pipe for inducing an upward flow therein and to cause the elevation of the load water and its solids, an air chamber surrounding the jet and having an outlet orifice concentric therewith, and means for supplying air to the 100 chamber for discharge through the outlet orifice.

5. A hydraulic elevator for load water and its solids comprising an upcast pipe having a discharge outlet and a load receiving opening spaced above the surface of the load water to permit atmospheric air to enter the lower end of the pipe between the inner surface thereof and the load water 105 passing upwardly therethrough, a submerged water jet axially aligned with the upcast pipe for inducing an upward flow therein and to cause the elevation of the load water and its solids, an air chamber surrounding the jet and having an outlet orifice 110 concentric therewith, and means for supplying air to the chamber for discharge through the outlet orifice at atmospheric pressure or less.

Dated at Quesnel, B. C., this 3rd July, 1926.

LEICESTER A. BONNER.
